Primary Examiner — Calvin E Vansant*Assistant Examiner* — Benjamin L. Gray(74) *Attorney, Agent, or Firm* — Warner Norcross + Judd LLP(57) **CLAIM**

The ornamental design for a door handle as shown and described.

DESCRIPTION

FIG. 1 is a front perspective view of the door handle embodying the new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The figures show features in broken lines that do not form any part of the claimed design. Further, the broken lines immediately adjacent the solid line portions of the design form the boundary of the design, with the broken lines forming no part of the claimed design.
